LOUIS D. VALETON, OF PHILADELPHIA, PENNSYLVANIA, ASSIGNOR TO
HENSEL, REICHERT, WOLFF, AND COMPANY.

Letters Patent No. 80,786, dated August 4, 1868.

IMPROVEMENT IN LOOM FOR WEAVING FRINGE.

The Schedule referred to in these Letters Patent and making part of the same.

TO ALL WHOM IT MAY CONCERN:

Be it known that I, LOUIS D. VALETON, of the city and county of Philadelphia, in the State of Pennsylvania, have invented a new and useful Loom for Weaving Fringe; and I do hereby declare the following to be a full, clear, and exact description of the construction and operation of the same, reference being had to the annexed drawings, making a part of this specification, in which—

Figure 1 is a front elevation,

Figure 2 a side elevation,

Figure 3 a rear elevation; and

Figure 4 a plan view of my improved loom.

The nature of my invention consists in providing a loom for weaving fringes with such additional machinery that it is capable of weaving and completing twist-fringe of any description.

To enable others skilled in the art to which my invention appertains to fully understand and use the same, I will proceed to describe its construction and operation.

In the drawings, A A A A represent the side-pieces, and A¹ A² A³ A⁴ the connecting-pieces or cross-bars of a suitable upright frame. This frame supports a main shaft, B, with a pulley, B¹, and several cams, to impart motion to different parts of the loom. It has also a gear-wheel, B², fastened to it, which, gearing into another wheel, C¹, drives a shaft, C, seen in figs. 1 and 2. This shaft C, with the aid of two cams, C² and C³, and levers C⁴ and C⁵, causes the movement of the harness connected to these levers.

The said levers are provided with friction-rollers c c¹, figs. 1 and 2, and with springs c² c³, to make these rollers bear constantly against their respective cams. Two wires or cords, c⁴ c⁵, are attached to these levers, whose upper ends are provided with branching wires, which connect them to the ends of four other levers, D D¹ D² D³, figs. 1, 2, and 4, of which D D¹ support the heddle E, and D² D³ the heddle E'.

To each end of the lower sides of these heddles is attached a spring, as seen in figs. 1 and 3, where said springs e e¹ have their lower ends fastened to a small cross-bar, e². These keep the heddles tight, and prevent any swaying motion which may be imparted to them by the warp while the loom is at work.

The lay or batten F is supported by two hangers, F¹ F², figs. 1 and 2, fastened to the frame above by bearings f f¹. Motion is transferred from the main shaft B by two cams, F³ F⁴, with two friction-rollers, f² f³, bearing on their surfaces, which rollers are fastened to two upright levers, F⁵ F⁶, figs. 1 and 3, pivoted at f⁵ f⁶ to a cross-bar, F⁷, and being connected to the batten by two connecting-rods, F⁸ F⁹, fig. 4.

Two large springs, f⁴ f⁵, fastened to the lower part of the batten and the rear end of the frame, tend to pull the batten back, and consequently keep the rollers f² f³ constantly in contact with the cams F³ F⁴.

f⁷ is the reed, fastened to the upper side of the batten, and serves to keep the warp properly separated.

The shuttle G, fig. 1, is an angular plate, the horizontal part of which is slotted and pointed. Through this slot g passes the weft, consisting of two cords, that form the substance for the twist-fringe. The said slot g is provided with a hook, g¹, which catches either one or the other cord of the weft, for a purpose hereinafter explained.

The shuttle is fastened to a bar, G¹, so as to be adjustable, which, being held to the batten by two metallic straps, g² g³, so as to allow a horizontal sliding motion, partakes of the motion of the batten also.

The sliding motion of G¹ is received from the main shaft by means of a cam, G², fastened to it, which cam bears against a roller, g⁴, on a lever, G³, which is pivoted to the frame at g⁵, and to a connecting-bar, G⁴, at g⁶. This bar G⁴ is pivoted to a lever, G⁵, at g⁷, which is pivoted to the frame at g⁸, and has a round pin, g⁹, fastened to its front end. This pin g⁹ plays up and down in a longitudinal slot in an inclined bar, G⁶, fig. 1, which bar is fastened to an adjustable bar, G⁷, at g¹⁰. The other end of the bar G⁶ is fastened to a bar, G⁸, at g¹¹, and the bar G⁷, at its opposite slotted end, is screwed to G⁸ at g¹². By these means, G⁶, with its slot, can be adjusted to any desired inclination.

The up-and-down movement of the pin g^9 , in the slot of the bar G^8 , makes the lever G^8 , which is pivoted to the hanger F^2 at g^{13} , swing right and left, which motion it transfers to the bar G^1 by a connecting-rod, G^9 . A spring, G^{10} , fastened to the bar G^1 and to the batten F , gives to the bar G^1 a tendency towards the left side, and a spring, G^{11} , fastened to the frame and to the lever G^8 , keeps the roller g^4 bearing against its operating-cam G^2 .

The twist in the fringes is effected by a revolving hook, H , fig. 1, which has its bearings in a plate, H^1 , and is provided with a small grooved pulley, h , and a cam, H^4 , having a step or tooth, h^1 , on its periphery, which, when it comes in contact with the pawl-lever h^2 , fastened to plate H^1 , figs. 1 and 2, suspends the revolution of the hook.

The plate H^1 is adjustable in a lateral direction by means of a slot, h^3 , and set-screw, h^4 . The plate H^2 , to which the plate H^1 is attached, is fastened to a bar, H^4 , which is suspended by two hanger-arms, H^5 and H^6 , figs. 1 and 2, from two levers, H^7 and H^8 , pivoted to the frame. The other ends of these levers are operated by two rods, H^9 H^{10} , fig. 3, to which they are pivoted, and these rods are pivoted to two levers, H^{11} H^{12} , figs. 3 and 4, which have their fulcra at h^6 h^7 on the cross-bar A^6 . These levers are operated on by two cams, H^{13} H^{14} , fig. 3, upon the main shaft B .

Two springs, h^{10} h^{11} , fastened to the levers H^{11} H^{12} , serve to keep the friction-rolls of the levers H^{11} H^{12} in contact with the cams H^{13} H^{14} .

The hook H receives its revolving motion from the shaft I , by means of a grooved cone-pulley, I^1 , and a cord, i , which is kept tight by a tension-spring, I^2 , and grooved roller, i^1 . From this shaft I , motion is transferred, by means of gear-wheels I^3 I^4 I^5 , to a pulley, I^6 , from which a belt communicates it to a pulley, B^1 , on the main shaft B . This affords a chance for changing the speed of the shaft B , by exchanging the gear-wheels mentioned for others of different diameter.

The lever H has also a lateral motion, in addition to its vertical movement, and this movement is caused by a lever, K , fig. 4, having a roller, k , bearing on a cam, K^1 , on main shaft B . A rod, k^3 , fastened to the frame, has a spring, k^2 , attached to its end, which, being also fastened to lever K , secures a constant bearing between roller k and cam K^1 , as seen in fig. 1.

A guide, k^4 , made of wire or other suitable material, secures a strictly vertical movement of the lever K , whose pin-shaped end, k^1 , bears on the inclined edge of an adjustable plate, K^3 , fastened to a lever, K^2 , with a fulcrum, K^5 , figs. 1 and 2.

The upper end of lever K^2 is connected to the bar H^4 by means of a conducting-rod, k^6 . A spring, k^7 , fig. 3, keeps the incline of plate K^3 in contact with the pin k^1 in the usual way. As the pin k^1 , on lever K , moves up and down, the lever K^2 is caused to swing to and fro, which motion is communicated to the bar H^4 and hook H .

To keep the bar H^4 always at the same distance from the batten F , it is provided at both ends with projecting pins, (of which one, h^6 , is seen in figs. 1 and 2,) made to slide vertically in a slot at the lower end of the hangers f^1 and f^2 . A movable bar, L' , supported by two guides, l^1 l^2 , to allow a vertical motion, has an angular and adjustable plate, l^3 , attached near its centre, and to this plate is fastened another plate, l^4 , which, by means of a set-screw and a suitable guide, l^5 , on the batten, holds a pin, l^6 , in such position that in its downward movement it enters between the fringe before it is twisted, and stops the twist from extending into the warp. The bar L' receives its vertical movement from two pins, l^7 l^8 , fastened to the levers H^7 and H^8 , figs. 2 and 3. A spring, l^9 , fastened to L' , and bearing against L , serves to keep bar L' in contact with pins l^7 and l^8 of levers H^7 and H^8 .

A horizontal rod or finger, l^7 , fastened to bar A' , figs. 2 and 4, serves to disengage the fringe from the hook H on its upward motion, after being twisted. An angular wire or finger, l^8 , fastened below bar A' , serves to disengage the pawl-lever h^2 from the tooth h^1 on the cam H^3 , on its downward movement, to allow the hook H to make the necessary revolution for twisting the fringe. A spring (not shown) bears on the other end of h^2 to keep its pawl-end in contact with cam H^3 . The finished fringe is wound up on a drum or spool, M , fig. 1, upon a shaft, M^1 . This shaft is moved by a ratchet-wheel, M^2 , and two pinions, m^1 m^2 , m being fastened to the ratchet-wheel and m^1 to the shaft M^1 .

The stud on which the ratchet-wheel turns forms the fulcrum for the pawl-lever M^3 , which receives its motion by means of a connecting-rod, m^2 , fastened to the hanger-arm F^1 of the batten, and to the pawl-lever, in such manner as to make an adjustable stroke. A driving-pawl, m^3 , is fastened to lever M^3 , and a retaining-pawl, M^4 , fastened to the frame, serve to operate the ratchet-wheel.

The fringe-cords are wound upon two spools, N N^1 , mounted on pins on the bar N^2 , which, by means of two wires or cords, n^1 n^1 , fig. 3, is suspended from the ends of two levers, N^3 N^4 . A rod, n^2 , connected with the two other ends of said levers, is fastened below to a lever, N^7 , and this, with the aid of a small friction-roller, n^3 , bearing on a cam, N^8 , upon shaft B , imparts a vertical motion to the bar N^2 , whose ends are fitted to slide in grooved guides N^5 N^6 , fig. 3, on the frame. A cord, N^7 , fastened at n^8 to bar N^2 , bears in a grooved rim of each spool N N^1 , with the aid of a spring, n^6 , fastened at its other end to the bar N^2 , effects the desired degree of tension. The two fringe-cords, from thence, are passed down through the loops of two tension-weights, n^5 n^4 , then up over a supporting-rod, n^3 , toward the shuttle.

The warp o is wound on a spool, o' , having a ratchet-rim, and being mounted upon a pin in a cross-bar, o^2 , fastened to the frame of the loom, a lever, O^3 , bearing on said rim, works as a pawl, and prevents the spool from turning and discharging the warp. From the spool the warp passes up over one or more small friction-rollers, o^1 , fastened to a small frame, O^4 , between the sides of the loom-frame. Thence the warp passes down through an eye, o^5 , which forms the upper part of a frame, O^5 , which is bent into the form of a swing, and forms a seat for a number of weights, with grooves at their ends, of which weights any desirable number can be supported

in O^5 to accomplish the right tension on the warp. Thence the warp passes up again over one or both of the rollers o^3 o^4 , thence down under a bridge, o^5 , and finally to the heddles and reed.

The operation of my invention is as follows:

As the warp and fringe-cords are parted by the action of the heddles, the cam G^2 on the main shaft depresses the lever G^3 , and, as has already been described, thereby moves the shuttle G between the raised and lowered sets of warp. In doing this, the hook g catches the lowered fringe-cord and carries it through between the warp so far as to allow the hook H (which is at the same time moved towards the shuttle) to catch the fringe-cord from the hook g , as soon as, by the action of the two cams H^{13} H^{14} upon the levers H^{11} H^{12} and H^7 H^8 , the bar H^4 , with the hook H , is lowered. This lowering process gives the right tension to the cord i , which has until now been slack, so that the hook H will revolve as soon as the lower end of the pawl-lever h^2 strikes the finger f , thereby disengaging the pawl from the ratchet-tooth h^1 on the cam H^3 .

As soon as the hook H catches the fringe-cord, the pin P is, by the same mechanism, moved down between the fringe-cord, and remains stationary until the twisting is finished, to prevent it from extending into the shed, and pushing the warp out of its straight direction. After the twist is completed, the hook H is raised again, and also the pin P , by the same mechanism that effected their lowering. This makes the pawl-lever h^2 free from the finger f , and, by the action of the spring bearing on it, the pawl-lever will catch against the tooth h^1 or cam H^3 , and stop any further revolution of H .

As the warp is carried forward to the twisting operation, the weight O^4 is gradually raised thereby, until it comes in contact with the inner end of lever O^3 , which causes its outer end to disengage itself from the ratchet on the spool O^1 , and allows the weight to drop as the spool rotates. A certain amount of warp is thus let off from the spool, until the lever again engages with the ratchet, which prevents any further rotation of the spool until the lever is liberated, as stated.

To facilitate the drawing of the necessary amount of fringe-cord through the warp by the hook H , the spools N N^1 on the bar N^2 are, by the action of cam N^8 on lever N^7 and the bar N^2 , lowered as soon as the hook has caught the cord from the shuttle, and lifted again as soon as the cord is twisted.

This loom will make a straight or parallel fringe if the cord I is removed and the revolving hook H made stationary in any of the known modes, as, for example, by inserting a small set-screw in one of its bearings.

Having thus described my invention, the following is what I claim as new herein, and desire to secure by Letters Patent:

1. I claim the slotted shuttle G , constructed with a hook, g' , and applied to operate in the manner and for the purpose specified.

2. I claim the twisting-hook H , having an intermittent rotary and vertical and horizontal motions, and arranged to operate in conjunction with the shuttle G , substantially as and for the purpose set forth.

3. I claim the spools N and N^1 attached to a bar, N^2 , having a vertical movement within the frame, and being connected with the lever N^7 through the medium of the rods n n^1 n^2 and levers N^3 and N^4 , all as herein described and for the purpose set forth.

4. I claim the pin P , applied and operating substantially as and for the purpose set forth.

To the above I have signed my name, this 4th day of May, 1868.

LOUIS D. VALETTON.
